UNITED STATES PATENT OFFICE.

WALTER H. FITZ GERALD AND GEORGE C. SMITH, OF CHICAGO, ILLINOIS.

FITTING FOR WATCH-CASE SPRINGS.

SPECIFICATION forming part of Letters Patent No. 316,953, dated May 5, 1885.

Application filed May 19, 1884. (No model.)

To all whom it may concern:

Be it known that we, WALTER H. FITZ GERALD and GEORGE C. SMITH, both citizens of the United States, and both residents of 5 Chicago, county of Cook, and State of Illinois, have invented certain new and useful Improvements in Fittings for Watch-Case Springs, of which the following is a specification.

This invention consists in an improvement in 10 means for fitting to watch-cases the catch and lift springs respectively employed for locking the hinged front when the latter is closed and for throwing open the same when it is unlocked. Heretofore the generally-adopted mode of con- 15 structing and fitting catch and lift springs to watch-cases has been to form the spring at one end of and in one piece with a curved bar which is fitted and secured within an inner annular recess in the case by means of one or 20 more pins or screws passing through the bar, which latter constitutes a base for the spring. Springs of such description are manufactured in large quantities, and in fitting them to watch-cases it becomes necessary to grade the 25 springs and otherwise adapt them to the size of case in which they are to be fitted. This frequently involves considerable time and labor, since, as is often the case, the base portion of the spring, as well as the spring proper, requires considerable filing either to adapt 30 the same to the width of the annular seat or recess in the watch-case or to grade or regulate the spring with reference to the degree of strength which will be best suited for the case 35 to which the spring is applied. For this reason, should either the catch or the lift spring break during use, the spring, including, of course, its long heavy base portion, must be thrown away and replaced by a new one, 40 which, if ordered by a repairer from a manu- 45 facturer, involves the following conditions, to wit: First, a spring having a base adapted in size to fit in the annular seat in the case, which, if not found in the spring supplied, must be attained by the repairer in fitting the same, and, next, a spring of the required grade, which, if not found in the spring supplied, must also be a subject for subsequent labor. From this it will be seen that either 50 the manufacturer must keep on hand a large variety of springs or the dealers must be subjected to an expenditure of time and labor in

fitting the springs, which will render the replacement of a new for a broken spring an undesirably expensive affair to the purchaser, 55 and in order to keep on hand a full line of such springs, sized and graded for different cases, the assortment must of necessity be large, so as to provide springs of different 60 grades with base portions made of sizes which shall vary with reference to the size of seat destined for their reception rather than with respect to the grade or quality of the spring.

It is the object of our improvement to remedy all of these defects, to cheapen and simplify 65 the manufacture of the springs, to render the replacement of a new for a broken spring a simpler, easier, and cheaper matter, and to admit of a uniformity in the action of the spring being attained in a simpler, better, and more 70 ready way than heretofore. To such end we provide a sectional base-ring for the springs, and form the latter separate from the base-ring, as hereinafter described, whereby a manufacturer can, in the first instance, fit in 75 the annular seat in the case the sectional base-ring, with the springs applied thereto, either before or after the base-ring has been fitted to the case, in which way should either spring subsequently break the spring can be changed 80 without any change whatever on the part of its required base-support.

In the annexed drawings, Figure 1 is a top plan view of an annular sectional base-support constructed in accordance with our in- 85 vention, and with the catch and lift springs applied thereto. Fig. 2 is an edge view thereof, and illustrates the lift-spring attached to one of the sections of said base-support. Fig. 3 is a like view illustrating the catch- 90 spring fitted in the annular base-support. Fig. 4 is a plan view of the under side of the annular base-support with the catch and lift springs applied thereto, the base-support being fitted in a watch-case, which is shown in 95 section. Fig. 5 is a sectional view taken transversely through the annular base-support on line $a-a$, Fig. 1, looking toward the catch-spring. Fig. 6 is a detail sectional view taken longitudinally through the catch- 100 spring and portions of the annular support which provides bearings for the springs, said view illustrating a stuffing-box formed at the middle of the spring. Figs. 7 and 8 are views

which include the several sections of the annular base, and also the catch and lift springs. Fig. 9 represents in part section a portion of one of the sections of the annular base adapted 5 to support a form of lift-spring, which is also included in said figure, and which differs somewhat in form from the lift-spring shown in some of the preceding figures.

Referring by letter to the several figures of 10 the drawings, in which like letters denote like parts, A indicates an annular sectional base-support for the catch and lift springs, which said support is adapted to fit within the annular groove or seating usually formed in the 15 center or body of a watch-case. This base-support consists of an annulus composed of several sections adapted to be detached from each other in order that they can be respectively introduced into the annular groove or 20 seating in the watch-case and connected together as they are placed within the same, so as to form a circular support therein for the springs, as indicated in Fig. 4, in which the annular base-support is shown fitted to a 25 watch-case, B. This annular support is preferably formed of three sections, a , a' , and a'' , detachably connected together at their ends in some suitable way, as, for example, by means of a tongue, a^3 , at the end of one section 30 adapted to fit in a notch at the opposing end of an adjoining section.

The preferred construction of lift-spring C and bow-shaped catch-spring D is that secured to us by Letters Patent of the United 35 States on or about the 22d day of April, 1884, which said springs are each double acting, as fully set forth in said patent.

The section a'' of the annular base-support is provided in its outer side with an oblong 40 notch or recess, E, in which the lift-spring is arranged to operate.

The lift-spring is pivoted at a point between its ends to the side wall of said recess, and is arranged with its tail end against an 45 abutment, F, and its opposite end normally projecting above the base-support, so as to hold the lid of the watch open when the latter is unlocked. When the lid is closed, however, this end of the lift-spring will be depressed into the recess E.

When the sections are properly fitted together, the opposing ends of the sections a a' do not meet, whereby a space, a^3 , Fig. 6, is left between the same for the stem, which passes 55 through and operates the catch-spring, or this space could be formed by recessing a solid section at a point between its ends. Said sections are also cut away at their opposing ends, so as to leave a space, a^6 , for the middle portion 60 of the spring at a time when the spring is to some extent straightened out, and at points back of such cut-away portions each one of these sections is provided with a recess, G, for receiving and providing a bearing for an end of 65 the catch-spring. The catch-spring is arranged loosely in the base-support and operates in the same way as the spring disclosed

by our said patent. Hence, when the stem is pushed inwardly, the spring will to some extent straighten out, while its ends will ride 70 along the side walls of the recess G. In this way the lift-spring will be confined between the case and the walls of one of the recesses in the sectional base, while the catch-spring will be arranged to work for the greater part in a 75 space within the said base.

This sectional base with springs of the character described, or of any other suitable construction, can be fitted to the case by the manufacturer, and, as the size of the base has 80 no reference to the grade of the springs, a saving on the cost of manufacture is obviously effected.

Should either spring break while in use, it can be replaced by a like spring without renewing any portion of the base. 85

While springs of other construction could be employed in connection with this sectional base or holder, yet the construction of springs secured to us by our said Letters Patent is 90 especially desirable, since, in the place of the large heavy springs heretofore required, we can employ comparatively light and cheap springs, which, having the double action, subserve all of the functions of a larger spring. 95

Figure 6 shows the catch-spring, made or provided with a stuffing-box, H, consisting of a hollow boss or small casing, and some suitable packing, I, having a bore for the passage of the stem, which latter will have a shoulder, 100 as usual, whereby when the stem is pushed in, its shoulder will strike against the stuffing-box, so as to partially straighten out the spring, and hence release or unlock the free edge portion of the hinged lid. 105

As herein illustrated, space is left between the opposing ends of sections a and a' of the annular holder or base, in which space the stuffing-box can extend out from the spring.

From the foregoing it will be seen that the 110 sectional base-support for the catch and lift springs can be readily taken apart and subsequently set up in the case, and that it can be readily adjusted therein, so as to bring the springs into proper position. 115

In Fig. 9 a lift-spring, C', is shown slightly different in form from the springs in some of the preceding figures, the main difference being in the form of its tail end C², which is adapted to enter a recess, E', at one end of 120 recess E. This spring, however, operates like the spring C, and one of the walls of recess E' constitutes an abutment for the same purpose as the abutment F, hereinbefore described.

Having described our invention, what we 125 claim, and desire to secure by Letters Patent, is—

1. The combination, with a watch-case, of a sectional base-support for the catch and lift springs, substantially as described.

2. The combination, with a watch-case, of an annular sectional support for the catch and lift springs, substantially as described.

3. The combination, with a watch-case, of

a sectional base-support for the catch and lift springs, fitted within an annular groove or seat in the body of the case, substantially as described.

5 4. The annular sectional base-support for the catch and lift springs of a watch-case, in combination with a lift-spring pivoted in a recess in said support, substantially as described.

10 5. The annular sectional base-support for the catch and lift springs of a watch-case, in combination with a catch-spring having its ends fitting loosely in recesses in the base-support, substantially as described.

15 6. The annular sectional support for the purpose described, provided at the opposing ends of two of its sections with recesses, and notches back of said recesses, in combination with the bow-shaped catch-spring fitted to operate in said recesses, substantially as de-
20 scribed.

7. The bow-shaped catch-spring provided with a stuffing-box, substantially as and for the purpose set forth.

8. The sectional base A, in combination with the catch-spring having a stuffing-box for the 25 stem to pass and work through, said box extending from the spring into a space in the said base, substantially as described.

9. The combination, with a watch-case, of a sectional base-support for the catch and lift 30 springs, adapted to be taken apart and subsequently fitted together in position in the case, substantially as described.
